UNITED STATES PATENT OFFICE.

LAWRENCE E. ROBBINS, OF ELLSWORTH, MAINE.

GYROPLANE.

Application filed October 3, 1927. Serial No. 223,798.

The present invention relates to aeroplanes and particularly to planes of this character having helicopter features. An object of the invention is to improve mechanism of 5 planes of this type.

Further objects are to provide novel and effective means for adjusting the propeller blades.

A further object is to provide for both 10 simultaneous and selective adjustment of the blades of two propellers through the same actuating medium.

A further object is to provide a construction whereby the helicopter propellers may 15 be used for raising the machine vertically and may then be converted into resistance planes for flying horizontally, and whereby the buoyancy of the machine may be increased.

20 Other objects are effectiveness in operation, simplicity and cheapness of construction and operation.

A further object is to strengthen certain of 25 the operating parts without lowering the efficiency thereof.

Other objects and advantages will appear 30 from the following description and will be set forth in the appended claims, and I do not wish to be limited in the scope of my invention except as I shall be limited by said claims.

In the drawings:

Figure 1 is a side elevation of an aeroplane 35 embodying the principles of my invention.

Figure 2 is a front view thereof on a reduced scale compared with Figure 1.

Figure 3 is a plan view of the same on the same scale as Figure 2.

Figure 4 is a fragmentary view showing 40 details of construction at the forward end of the machine, with parts of the body broken away, on the line 4-4 of Figure 3, showing the relation of parts interiorly of the body and parts of the various sleeves on the drive 45 shaft in section or broken away to show the relation of the parts. This view is on a scale enlarged over Figure 1.

Figure 5 is a section on the line 5-5 of Figure 4 and on the same scale as Figure 4.

Figure 6 is a section on the line 6-6 of Figure 4 on an enlarged scale over Figure 4, Figures 5 and 6 showing the mechanism for angularly adjusting the propeller blades at the forward end of the machine.

Figure 7 is a detail section on the line 7-7 of Figure 5 and on an enlarged scale com-

pared with Figure 5, showing the connection of brace members with the propeller blade.

Figure 8 is a section on the line 8-8 of Figure 2 on an enlarged scale compared therewith and showing the construction of the helicopter propeller shafts and the operating connections of the blades to the shaft and of the shaft to operating and driving mechanism. 60

Figure 9 is a section on the line 9-9 of Figure 8 through the propeller blades on the same scale as Figure 8.

Figure 10 is a section on the line 10-10 of Figure 8, showing parts of the blade adjusting mechanism. 70

Figure 11 is a detail on an enlarged scale, showing other of the blade adjusting mechanism.

Figure 12 shows a fragment of the aero- 75 plane body, on an enlarged scale over Figure 1, with adjusting and drive mechanism shown in dotted lines.

Figure 13 is a section on the line 13-13 of Figure 12, showing the mechanism in a view 80 at right angles to Figure 12 and on the same scale.

Figure 14 is a detail section on the line 14-14 of Figure 13, showing certain adjusting levers and adjustment mechanism on an 85 enlarged scale compared with Figure 13.

Figure 15 is a section on the line 15-15 of Figure 13, showing drive connections for the helicopter blades.

Referring to the drawings in detail by reference numerals, the same numerals designating the same parts in all views of the drawings, 10 designates the body or fuselage of the aeroplane, having the usual rudder 11 at the rear end, wheels 12 for supporting the 95 body on the ground, and a skid 13 cooperating with the wheels.

The present machine is designed to be lifted vertically off the ground and when a proper level has been reached to convert the helicopter lifting propeller blades into planes 100 affording resistance to the air and providing buoyancy for the machine. At the forward end of the machine is a propeller effective for causing horizontal travel of the machine. 105 The helicopters, of which there are two in number, are designated generally by the numeral 14 and the propeller for horizontal travel is designated generally by the numeral 15. The propeller 15 and the helicopter propellers 14 are driven by an engine 16, the propeller 15 through shaft 17 supported in a 110

bearing sleeve 17^a having three bracket arms 17^b formed integral therewith and connected with the casing of the engine, and the helicopter propellers through shafts 18 in driven connection with the engine through the differentials 19, 20 and 21, the shafts 18 extending horizontally from the sides of the fuselage and being in driving connection through gears 22 and 23 respectively on the shafts 18 and on a hollow vertical shaft 24 to which the blades are attached for rotation therewith through the medium of hubs 25 secured to the shaft by pins 26. The gears 19, 20 and 21 and the gears 22 and 23 are surrounded by casings 27 and 28 respectively, said casings being connected by tubular members 29 and 30 in the nature of casings, which afford protection for the shafts 18. The hollow shafts 24 are likewise protected by tubular members 31 also connected to the casings 27 and 28. The tubular member 31 is in the nature of a shaft and is provided with bearings 32 and 33 at its opposite ends for the hollow shaft 24. The tubes 29 and 30 are also provided with bearings 34 at their opposite ends, the bearings at one end only being shown. A similar bearing is provided in the tubular members 35 and 36 for the drive shaft 37 connected in driven relation with the engine. The upper end of the tube 31 serves as a support for the hubs 25 rotatably mounted thereon, the tubular shafts 31 extending into a snugly fitting countersunk portion 38 of the bore 39 extending through the hub.

Extending longitudinally through the bore of the shaft 24 is an adjusting rod 40 having a head 41 at its upper end from which project a pair of arms 42 extending rearwardly and having portions 43 thereof lying in parallelism with the tubular casing 31, said portions being substantially square in cross section and provided on one surface with ratchet teeth 44 constituting ratchet bars which are in cooperative connection with the gears 45 secured to threaded pins 46 rotatably mounted in suitable brackets 47 secured to a support 48 extending laterally from the tubular shaft 31. The threaded portions of the pins 46 are in connection with the threaded apertures of lugs 49 rotatably mounted on diametrically opposite portions of an annular member 50 which is in turn rotatably mounted on the hubs 25 below the propeller blades 51 of the helicopter. The members 50 are provided at their lower ends with flanges 52 and 53, the former resting on a flanged annulus 54 secured by pins 55 to the hub, with the flange 56 thereof affording a bearing surface for the flange 52 of the member 50. The upper flange 53 is provided with a mutilated crown gear 57 providing spaced groups of teeth 58, one group for each propeller blade, of which in the present showing there are four in number. The propeller blades 51 are mounted for

angular adjustment on the hubs 25 by means of rods 59 detachably secured to the hubs by a threaded connection 60. The inner ends of the blades are provided with sleeves 61 from which project sectors of gears 62, the teeth of which are adapted to cooperate with the teeth 58 of the crown gear herein described. Through this mechanism it will appear that when the shaft 40 is actuated vertically, the blades 51 will be given a turning movement through the ratchet bars 44, the pins 46 and the members 50. The means for operating the shaft 40 from the driver's seat in the aeroplane body will be presently described.

Brace members 63 are secured to the hubs by arms 64 and 65 and have pivotal connection with the propeller blades at 66 to provide for the turning movement of the blades. The slots 67 in the blades in which this connection is made are of sufficient length to provide for turning movement of this character. Brace wires 68 are provided attached to the under side of the blades and to the rear of the hub for bracing the blades from the side opposite to the brace members 63 and may have branches 68^a connecting with the brace members 63. Other truss rods of the character of 68 are provided at 69 between the aeroplane body and the tubular shaft 31 and at 69^a beneath the body, and attached thereto and to the shaft casings 29 and 30 two other truss rods are provided, one extending forward and one rearward and connected to the bottom of the fuselage. The shafts 31 may be further braced by stays 70 extending therefrom and connected to the casing 29. The casing 29 for the gears may be provided with a removable cover 71 in order to provide access to the said gears.

Secured to the casing 28 by a bracket 72 is a vertically extending rod 73 having a sleeve 74 slidably mounted thereon, said sleeve being provided with a projecting arm 75 having a yoke 76 at its outer end connected in the groove of a collar 77 secured on the lower end of the adjusting rod 40. In the ends of the rod 73 are journaled pulleys 78 and 79 respectively at the upper and lower ends of the rod, about which are passed cables 80 and 81 each having one end thereof connected to the sleeve 74, the cables extending over pulleys 82 and 83 and to a position adjacent the driver's seat, where they are connected to an operating lever 84, at 86 and 87, on opposite sides of its pivot 85 which is in the nature of a screw bolt by which the lever 84 is attached to the differential casing 27. Through this lever and the connection thereof to the rod 40 just described, the helicopter blades may be simultaneously given an angular adjustment relative to the hubs on which they are mounted, in this manner presenting the blades at various angles to the atmosphere. By this mechanism, the blades may be ad-

justed selectively in opposite directions by the movement of the lever from its central position in which the blades are extended horizontally to points on the dial 88 having spaced apertures 89 therein to cooperate with the detent 90 on the end of a holding lever 91 mounted on the lever 84. Provision is also made in connection with the adjustment mechanism herein described for adjusting the propeller blades simultaneously in the same direction, the means by which this is accomplished constituting slidable blocks 92 mounted in suitable slideways 93 secured interiorly to the body 10 and extending vertically relative to the bottom thereof. The blocks 92 are provided with spaced pulleys 94 and 95 about which the cables 80 and 81 are respectively trained, the cables passing about pulleys 96 and 97 and pulleys 98 and 99 on each side of the sliding block and secured to the slideway centrally thereof and intermediate of the position of the pulleys 94 and 95 at all times. The sliding blocks are manipulated through the hand lever 100 secured to the shaft 101, which is journaled at 105 to the side walls of the fuselage, and through arm 102 secured to said shaft, and through a bell crank 103 connected with the arm 102 of a link 104. By means of the lever 101 which operates the blocks at both sides of the casing simultaneously in the same direction, it will be seen that the upper or lower cables 80 or 81 may be given more or less tension, or more or less slack at the will of the operator, and the propeller blades of the helicopters may thereby be adjusted simultaneously in the same direction.

The propeller 15 at the front of the machine comprises a hub 106 and propeller blades 107, as shown two in number, arranged for angular adjustment on the hub in a manner similar to that described in connection with the helicopter propellers. The blades are secured to the hub 106 by means of rods 108 threaded into the hub and having their opposite ends supported by brackets 109 similar to the brackets 63 on the helicopter blades, the rods 108 having pivotal connection with the brackets 109 through eyes 110 with which they are threadedly connected, the eyes 110 being held in place by the rods 108 and between spaced members 111. The portions 110^a of the brackets 109 are formed so as to be detachable therefrom for convenience of assembly as shown at 110^b. A similar construction is provided in connection with the helicopter blade braces 64 at 64^a. The adjustment of the blades is effected through a sector of gear teeth 112 mounted on each propeller blade and articulating with a similar sector 113 secured to the flange 114 of a collar 115, the other end of said collar carrying a similar flange 116 on which are rotatably mounted lugs 117 at diametrically opposite points, the lugs being provided with threaded apertures 118 to re-

ceive the threaded pins 119 similar to the pins 46 hereinbefore described in connection with the helicopter adjustment. Said pins are rotatably mounted on a supporting flange 120 of the collar 121 which has a sleeve 121^a integral therewith and rotatably mounted on the bearing sleeve 17^a of the shaft 17. The threaded pins are journaled in bearings 122 secured to the supporting flange in the same manner as the mounting of the pins 46, the pins being rotated through a gear and ratchet bar connection in the same manner as in connection with the helicopter, the ratchet bars being shown at 123 and the gears at 124. The ratchet bars are secured to the flange 125 of the collar 126 mounted on the sleeve 121^a and having a loose sliding connection therewith, and said ratchet bars are adapted to be moved longitudinally of the shaft 17 by means of the rod 127 having a yoke 128 connected with the collar 126 and riding in the groove 129 formed therein, the opposite end of the rod 127 being connected through a link 127^a with a hand lever 127^b pivoted at 127^c to the bottom of the fuselage. The rod 127 is preferably incased and supported by a tubular casing 127^d with which it has sliding connection. Driving connection between the shaft 17 and the helicopters is effected through a shaft 130, and chains 130^a trained about gears on the shafts 17 and 130, the gears not being visible in the drawings.

The operation of the mechanism of the aeroplane is as follows: When it is desired to make a flight with my machine the engine is started, which causes the helicopter and propeller 15 to operate simultaneously, both being in flat position until a sufficient high rate of speed is developed. The blades of the propeller 15 are at first turned to the flat position by manipulation of the rod 127, while the helicopter blades are set through the lever 100 at an angle to produce a vertical draught on the machine, whereupon the machine will be caused to rise and the blades are maintained at this angle until the proper height has been reached. Then the propeller blades are tilted by manipulation of the rod 127, causing the desired horizontal draught. Then the angle on the helicopter blades is released until the aeroplane will travel on a level course. The blades of the helicopters will act as the planes of an ordinary aeroplane, affording resistance against the air and giving the aeroplane sufficient buoyancy to remain aloft. The helicopter blades will continue to revolve and in their forward movement will increase the air resistance by their movement thereagainst. In this manner a smaller resistance will be necessary to keep the aeroplane aloft. In turning movements and when it is desired to bank the aeroplane and for the purpose of keeping the aeroplane equilateral, the position of the helicopter blades may be adjusted separately therefor through the lever 84, but when

it is desired to use them for helicopter purposes, or to descend to a lower level, the position of the helicopter blades will be adjusted simultaneously through the lever 100 which 5 may be latched in various positions of adjustment on the rack 100^a through the pawl 100^b as shown in Figure 12.

When it is desired to make a landing it is merely necessary to reverse the angle of the 10 blades on the propeller 15, stopping the aeroplane over the place upon which it is desired to land, then turning the propeller blades to a flat position and releasing the angle of the 15 blades on the helicopters, so that the aeroplane may be allowed to settle gradually to the ground, requiring a very small space for a landing area. The plane is provided with a high skid 13 in order that it may rest in a 20 position on the ground so that the helicopter blades will be in a horizontal position.

Having described my invention, what I claim is:

1. In an aeroplane, a pair of helicopter propellers mounted thereon, shafts for supporting the helicopter propellers, a shaft concentric therewith for rotating the propeller blades, an adjusting rod movable longitudinally of said supporting shaft, ratchet bars secured to said adjusting rod, a hub on the 25 supporting shaft, propeller blades rotatably mounted on said hub, a collar having a gear connection with said propeller blades and rotatable on said hub, means actuated by said ratchet bars for rotating said collar, and flexible 30 means connected to said adjusting rod for operating the same from the driver's seat of the aeroplane.

2. An aeroplane having a body, vertical tubular supporting members secured thereto 40 on opposite sides thereof, propellers mounted on said tubular members and comprising hubs having propeller blades mounted thereon and angularly adjustable relative thereto, said hubs being rotatably connected with said tubular members, a tubular shaft secured to said hubs and in driven connection with the power of the aeroplane, means on said hubs for adjusting said blades relative to the hubs, said adjusting means comprising a collar rotatably mounted on the hubs and having gear connection with said blades, threaded pins mounted on said hubs and threadedly connected with said collar for rotating the same,

55 gear and ratchet bar connections for rotating the said threaded pins, an adjusting rod slideable longitudinally of said shaft, means for securing said ratchet bar connections to said adjusting rod, flexible means for moving said adjusting rod, and a lever to which said flexible means are secured adjacent the driver's 60 seat.

3. An aeroplane comprising a body, a pair of helicopter propellers supported from said body and arranged on opposite sides thereof, said helicopter propellers comprising hubs having adjustable propeller blades thereon, means for adjusting said propeller blades including pairs of flexible members, one of each pair of which operates the blades in one direction and the other of each pair in the opposite direction, vertically slideable blocks having pulleys at their opposite ends, slideways for said blocks, pairs of pulleys on said slideways adjacent said blocks on opposite sides thereof, one of each of said pairs of flexible 70 connections being trained under one of the pulleys of each pair and over the upper pulley on said block, and the other of said flexible pairs being trained over one of the pulleys of said pairs and under the pulley on the lower 80 end of said block, a lever pivoted intermediate of its ends centrally of the aeroplane, the ends of said pairs of flexible means being secured to said lever at equal distances on either side of the pivotal point, and means for 85 simultaneously shifting said blocks.

4. In an aeroplane, a body, propellers, means for driving said propellers and carried by said body, said propellers each including a hub with blades mounted thereon for angular 90 adjustment relative to said hub, brackets secured to said hub for supporting said blades, rods threaded to the hub and extending into said blades, spaced members in said blades to receive the rods therethrough, eyed members 95 secured to said brackets and received between the spaced members to receive the rods in the eyes thereof for pivotal connection therewith, means for adjusting the blades of one propeller relative to its hub and means for selectively and simultaneously adjusting the angle of the blades of the remaining propellers with 100 respect to their hubs through a single means.

In testimony whereof I affix my signature.

LAWRENCE E. ROBBINS.
